UNITED STATES PATENT OFFICE.

JAMES C. SKELTON, OF SANTA MONICA, CALIFORNIA.

SANITARY LAUNDRY BOX.

Application filed June 15, 1923. Serial No. 645,575.

To all whom it may concern:

Be it known that I, JAMES C. SKELTON, a citizen of the United States, residing at Santa Monica, in the county of Los Angeles 5 and State of California, have invented new and useful Improvements in Sanitary Laundry Boxes, of which the following is a specification.

Although my present invention may be 10 referred to as a ventilated laundry box, it should be understood that boxes of the construction herein described may be used for a wide variety of purposes, all of my boxes being, however, provided with means for 15 permitting a free circulation of air.

It is an object of this invention to provide a laundry box, or the like, which shall be of workmanlike construction and of attractive appearance, but may nevertheless be inexpensively made; and, in one preferred embodiment of my invention, I may build my 20 ventilated box in sections, thereby adapting the same to be shipped in a "knock-down" condition, and to be expeditiously assembled 25 by a dealer or purchaser.

Although it is an object of this invention to provide a box having inclined slats in its sides and adapted to be open at the top, when a box embodying my invention is to 30 be used as a storage place for foods, or the like, it should be understood that fly-wire netting may also be employed; and that any desired alternative or additional openings 35 may be provided, it being possible, for example, to pivot an entire side section upon one of the bolts which may optionally be used to hold the sections or parts of my boxes together; and possible also to use the mentioned inclined slats as supports for 40 removable shelves, optionally placed within my ventilated box.

Other objects of my invention will appear from the following description of a preferred embodiment thereof, and from the 45 appended claims, taken in connection with the accompanying drawings, in which—

Fig. 1 is a perspective view of a laundry box, or the like, embodying my invention.

Fig. 2 is a vertical section of a similar box, 50 this view being taken in a plane such as the plane 2—2 of Fig. 1, the box of Fig. 2 being, however, shown as provided with fly-wire.

Fig. 3 is a horizontal section of a box such 55 as is shown in Figs. 1 and 2, and the view shown in this figure may be regarded as taken on the line 3—3 of Fig. 1.

Referring in detail to the parts of that specific embodiment of my invention which I have chosen for purposes of illustration, the side or vertical walls of my box may be 60 regarded as consisting essentially of a pair of substantially rectangular end frames 1, 1', and a pair of substantially rectangular side frames 2, 2', all of said frames being preferably formed of broad vertical strips 3, 65 spaced apart by horizontal strips 4, 4' and supporting inclined slats 5. Although the mentioned frames may be connected or supported in any suitable way, I find it advantageous to secure each end frame permanently to a pair of corner posts 6, and to provide additional means for removably securing the side frames 2, 2' to the same posts, in such manner as to form an enclosure, which may be completed by the addition 70 of a suitable bottom plate 7 and a suitable cover.

While various alternative constructions might obviously be employed, I prefer to form my bottom plate from slats 8 secured to cleats 9, the latter being preferably of sufficient length to overlie the horizontal strips 4', comprised in the respective end frames, my preferred construction being such that, although the bottom 7 may interlock with the mentioned associated parts, free circulation of air shall be permitted by the openings between the slats 8, and such also that the bottom may be freely removable from the inside, although not free 90 to move downward below the position indicated in Fig. 2.

Any one of a variety of constructions might be employed in the providing of a suitable closure for my ventilated box, but 95 I prefer to employ a removable cover 10, provided with a central opening 11, protected by a plate 12, and provided with a handle 13; and, in order to facilitate a positioning of the said cover, the corners thereof may optionally be provided with notches 14, adapted to interfit with the respective posts 6.

Whether or not the top element of my ventilated box is used as a removable cover, I may optionally employ bolts, such as the short bolts 15 extending through the strips 3 and the posts 6, or such as the longer bolts 16, 16' extending entirely across one side of my ventilated box, to secure the 110 parts thereof in their indicated relative positions; and, when the longer bolts 16' are

employed, one or more of these bolts, such as the lower bolt 16', may optionally be used as a pivot bolt, in such manner as to enable an entire side 2 to swing out in a vertical plane, thereby providing a lateral opening for my box; and this construction is especially advantageous when, by reason of the placing of an additional object such as the shelf or receptacle 17 upon the top of the posts 6, whose upward extensions 18 assure a suitable spacing, the cover 10 becomes comparatively inaccessible.

When a box of the character described is provided with a pivoted side, of the character just described, and especially when such a box is to be employed for the storage of food, or the like, I may provide the interior thereof not only with removable shelves 19, whose ends may be supported by the outwardly and downwardly inclined slats 5 these being intended primarily to exclude direct sunlight while permitting a free circulation of air, but also with fly-wire 20 or the like, to exclude insects, this being optionally secured to the outside faces of the frames 1, 1' and 2, 2' and to the lower surfaces of the ventilated box 7 and the ventilated top 10, as best shown in Fig. 2.

It will be obvious that a box of the character described may optionally be provided with any preferred type of casters; and, although I have herein described and shown but two types of complete ventilated boxes, each provided with rather heavy and ornamental corner posts, these posts preferably extending both below the bottom and above the top and being used to connect substantially rectangular frames shown as comprising strips somewhat narrower than said posts, and although I have shown my boxes as provided also with a top cover which extends over and may be supported by said side frames, it should be understood that various features of my invention might be independently employed, and also that various additional modifications might be made therein without departure from the spirit and scope of my invention, as the same is indicated above and in the following claims.

What I claim is:

1. In a ventilated box, vertical walls comprising substantially rectangular sections secured to corner posts, additional substantially rectangular sections removably secured to said corner posts, each of said rectangular sections being provided with inclined slats and a ventilated bottom plate adapted to be removably mounted at the bottoms of the vertical walls with the corner posts extending below the bottom plate.

2. In a ventilated box, vertical walls comprising substantially rectangular sections secured to corner posts, and additional substantially rectangular sections removably se-

cured to said corner posts, each of said rectangular sections being provided with inclined slats secured by broad strips.

3. In a ventilated box, vertical walls comprising substantially rectangular sections secured to corner posts, and additional substantially rectangular sections removably secured to said corner posts, each of said rectangular sections being provided with inclined slats secured by broad strips comprised in a frame. 75

4. In a ventilated box, vertical walls comprising substantially rectangular sections secured to corner posts, and additional substantially rectangular sections removably secured to said corner posts, each of said rectangular sections being provided with inclined slats secured by broad strips comprised in a frame, said strips being narrower than said posts. 80

5. In a ventilated box, vertical walls comprising substantially rectangular sections secured to corner posts, and additional substantially rectangular sections removably secured to said corner posts, each of said rectangular sections being provided with inclined slats secured by broad strips comprised in a frame to which fly-wire may be secured. 90

6. In a ventilated box, vertical walls comprising substantially rectangular sections secured to corner posts, and additional substantially rectangular sections removably secured to said corner posts, each of said rectangular sections being provided with inclined slats adapted to support shelves. 95

7. In a ventilated box, vertical walls comprising substantially rectangular sections secured to corner posts, additional substantially rectangular sections removably secured to said corner posts, each of said rectangular sections being provided with inclined slats, and one of said sections being pivoted and a ventilated bottom plate adapted to be removably mounted at the bottoms of the vertical walls with the corner posts extending below the bottom plate. 100

8. In a ventilated box, vertical walls comprising substantially rectangular sections secured to corner posts, additional substantially rectangular sections removably secured to said corner posts, each of said rectangular sections being provided with inclined slats, and one of said sections being secured by means comprising bolts and a ventilated bottom plate adapted to be removably mounted at the bottoms of the vertical walls with the corner posts extending below the bottom plate. 110

9. In a ventilated box, vertical walls comprising substantially rectangular sections secured to corner posts, additional substantially rectangular sections removably secured to said corner posts, said vertical walls being surmounted by a cover extend- 125

ing thereover and a ventilated bottom plate adapted to be removably mounted at the bottoms of the vertical walls with the corner posts extending below the bottom plate.

- 5 10. In a ventilated box, vertical walls comprising substantially rectangular sections secured to corner posts, additional substantially rectangular sections removably secured to said corner posts, said vertical walls
10 being surmounted by a cover extending thereover and interfitting with said posts and a ventilated bottom plate adapted to be removably mounted at the bottoms of the vertical walls with the corner posts extending
15 below the bottom plates.
11. In a ventilated box, vertical walls comprising substantially rectangular sections secured to corner posts, additional substantially rectangular sections removably secured to said corner posts, said vertical walls being surmounted by a cover extending thereover and provided with a ventilating aperture and a ventilated bottom plate adapted to be removably mounted at the
20 bottoms of the vertical walls with the corner posts extending below the bottom plate.
- 25

12. In a ventilated box, vertical walls comprising substantially rectangular sections secured to corner posts, additional substantially rectangular sections removably secured 30 to said corner posts, said vertical walls being surmounted by a cover extending thereover and provided with a ventilating aperture protected by a plate and a ventilated bottom plate adapted to be removably mounted at 35 the bottoms of the vertical walls with the corner posts extending below the bottom plate.

13. In a ventilated box, vertical walls comprising substantially rectangular sections 40 secured to corner posts, additional substantially rectangular sections removably secured to said corner posts by means comprising bolts, one of which may serve as a pivot and a ventilated bottom plate adapted to be 45 removably mounted at the bottoms of the vertical walls with the corner posts extending below the bottom plate.

In testimony whereof I have signed my name to this specification.

JAMES C. SKELTON.
